(57) **CLAIM**

We claim the ornamental design for a height adjustable workstation, as shown and described.

DESCRIPTION

FIG. 1 is a front perspective view of a height adjustable workstation according to the present invention;

FIG. 2 is a front view of the height adjustable workstation of FIG. 1;

FIG. 3 is a rear view of the height adjustable workstation of FIG. 1;

FIG. 4 is a right side view of the height adjustable workstation of FIG. 1;

FIG. 5 is a left side view of the height adjustable workstation of FIG. 1;

FIG. 6 is a top view of the height adjustable workstation of FIG. 1; and,

FIG. 7 is a bottom view of the height adjustable workstation of FIG. 1.

The broken lines shown in the drawings illustrate portions of the height adjustable workstation and form no part of the claimed design.
